UNITED STATES PATENT OFFICE.

JOHN V. KRANEBEEL, OF BUFFALO, NEW YORK.

WATER-POWER MOTOR.

Application filed October 30, 1920. Serial No. 420,623.

To all whom it may concern:

Be it known that I, JOHN V. KRANEBEEL, a citizen of the United States, residing in Buffalo, in the county of Erie and State 5 of New York, have invented new and useful Improvements in Water-Power Motors, of which the following is a specification.

This invention relates to a water power motor of the class which are designed to 10 utilize the power of flowing streams or rivers.

It is the object of this invention to provide a motor of this character which embodies one or more wheels against which the 15 flowing water is adapted to press, which can be easily installed in any available water course from which power is to be taken, which can be easily adjusted to suit the height of the water in the stream or the 20 power desired, and which is very simple and durable in construction and not liable to get out of order under the severest strain to which the same may be subjected.

In the accompanying drawings:

25 Figure 1 is a side elevation of my improved water motor. Figure 2 is a horizontal section taken on line 2—2, Fig. 1. Figure 3 is a vertical longitudinal section of the water motor. Figures 4, 5 and 6 are fragmentary 30 sections taken in the correspondingly numbered lines in Fig. 3. Figure 7 is a cross section taken on line 7—7, Fig. 1. Figure 8 is a fragmentary horizontal section taken 35 on line 8—8, Fig. 7. Figure 9 is a fragmentary vertical longitudinal section, similar to Fig. 3, but showing a water wheel raised higher than those shown in Fig. 3. Figures 10 and 11 are perspective views of 40 parts of the means for locking a water wheel in various vertically adjusted positions.

Similar characters of reference refer to like parts throughout the several views.

The stationary main frame of this motor 45 may be supported in any approved manner over the stream from which power is to be taken and the same may be any suitable construction to support the various working parts, that shown in the drawings being merely illustrative of one adapted for this 50 purpose and consisting generally of two lower longitudinal beams 15, two upper longitudinal beams 16, a plurality of upright posts 17 connecting the longitudinal beams, lower and upper upright plates 18, 55 secured lengthwise to said posts, transverse bars 19 connecting said lower plates,

and transverse platforms 20 connecting said posts and lower plates.

Journalized horizontally and transversely in bearings on the lower part of this frame 60 is the main driving shaft 21 to which the power of the flowing water is transmitted by my invention and from which this power may be delivered in various ways, for instance, by a pulley 22 arranged at one end of the driving shaft and adapted to receive a driving belt. To this driving shaft the power of the flowing stream below is transmitted by one or more water wheels through the medium of intermediate mechanism. As shown 65 in the drawings, two water wheels are arranged on opposite sides of the driving shaft and as the construction of the same, as well as the means for transmitting their power to the driving shaft and the means 70 for raising and lowering the same and locking them in position are alike respecting both wheels, the following description of one wheel and mechanism associated therewith 75 will apply to both of them.

80 23 represents the axle of one of the water wheels which is arranged horizontally and paralleled with the driving shaft at a distance from the latter. This axle is journaled at its opposite ends in bearings arranged on the outer ends of two vertically swinging rock arms 24 which latter are pivoted at their inner ends on the driving shaft so as to turn concentrically thereto. Motion is 85 transmitted from this axle to the driving shaft by a pair of belts 25 preferably of the chain type arranged lengthwise on the opposing sides of the rock arms and each passing at its outer and inner turns around sprocket wheels 26, 27 secured respectively to 90 said axle and driving shaft, as best shown in Figs. 1 and 2. 28 represents the two disk-shaped heads of the water wheel which are secured to the axle, 29 a cylindrical drum or hollow hub interposed between these heads 95 at a distance from the peripheral edges of the latter, 30 a plurality of blades or wings arranged in an annular row around the hub and between the heads, 31 a plurality of rods which are secured to the heads and pass through sleeves 32 at the inner ends of the blades so that the latter can swing vertically, and 34 a plurality of pairs of stops arranged 100 radially on the inner sides of said heads and serving to limit the folding and unfolding motion of said blades.

105 When this wheel has its lower part sub-

merged in the water of a flowing stream, as shown in Fig. 3, each blade while passing on the lower part of the wheel rests in a radial position against the rear side of one 5 pair of stops 34 so that this blade receives the pressure of the water and transmits the same to the axle and as it rises out of the water the same folds against the front side of the next following pair of stops which 10 permits the blade to withdraw from the water without retarding the rotation of the wheel and thus increasing the output of power. The blade remains in this folded position while passing over the top of the 15 wheel and then unfolds on the descending side of the same preparatory to again entering the water.

With each water wheel is associated an 20 adjusting mechanism whereby the same may be raised or lowered in the water to suit the level of the stream or vary the power which is derived from the same or the wheel may be lifted entirely out of the water for the purpose of inspection, adjustment 25 or repairs. In its preferred construction each of these wheel adjusting devices is constructed as follows:

35, 35 represent a pair of vertically movable slides which are guided in ways 36, 30 36 on the lower plates 18 of the main frame and each of which is connected with one of the rock arms of a water wheel by an adjusting line 37 which has an upwardly trending bight or turn passing around a 35 guide pulley or wheel 38 on the adjacent part of the lower frame plate 18. Each of these slides may be raised or lowered by an adjusting screw 39 engaging its upper part with a threaded opening in the respective slide and journaled near its lower end in a bearing 40 on the main frame so that this screw can turn but not move lengthwise. At its lower end the adjusting screw 40 is provided with a driven bevel gear wheel 41 which is arranged between two driving bevel gear wheels 42, 43, which are splined on a longitudinal intermediate shaft 44 so that either one or the other of the driving gear wheels may be engaged with said driven gear wheel for turning the adjusting screw in one direction or the other and either raising or lowering the water wheel and associated parts. The intermediate shaft preferably extends over the main driving shaft so as to serve as an intermediate shaft for the other water wheel on the same side of the frame and this intermediate shaft is rotated constantly by a worm 45 arranged on the main driving shaft and meshing with a worm wheel 46 on the intermediate shaft as shown in Figs. 1 and 7. When both driving gear wheels 42, 43 are out of engagement with the driven gear wheel 41 the latter remains at rest and the respective water wheel is held by its ad-

justing screw 39 in whatever position the same may be left. The two driving gear wheels on the same end of the water wheel are shifted simultaneously lengthwise of the respective intermediate shaft for engaging 70 either one of these driving gear wheels with the driven gear wheel or disengaging the same therefrom by means of a vertically swinging shifting lever 47 having two forks 48, 49 which engage respectively with annular grooves 50, 51 in the hubs of the driving gear wheels 42, 43. For the purpose of ensuring simultaneous raising and lowering of the rock arms supporting opposite ends of the water wheel, the two 75 shifting levers 47 for each water wheel arranged on opposite sides of the water motor are connected with a horizontal rock shaft 52 which is journaled transversely in suitable bearings on the main frame and 80 provided with an upwardly projecting lever 53 for operating the same. Each of these operating levers is locked either in its neutral central position or in either one or the other of its operative positions by a segmental rack 54 secured to the adjacent cross bar 19 of the main frame and a locking dog 55 guided in the operating lever and movable into and out of engagement with this rack by a handle 56 connected by a 85 rod 57 with the locking dog.

Equalizing means are provided for causing the outer or free ends of the rock arms which support the axle of the water wheel to rise and fall in unison and thus avoid 100 any straining of the parts or cramping and binding of the axle in its bearings, said equalizing means being combined with locking means which support the load upon these rock arms at the outer ends thereof. 105 In the preferred embodiment these equalizing and locking means are constructed as follows:

58, 58 represent two gear segments mounted on the supporting rock arms of each 110 water wheel and each having its row of teeth arranged concentrically with the axis of the driving shaft and engaging with a gear pinion 59. Arranged transversely in front of the pair of gear segments is an 115 equalizing shaft 60 which is journaled in suitable bearings on the main frame and has the gear pinions 59 secured thereto so that the same are compelled to turn together. By this means both rocking supporting arms of the water wheel are caused to rise and fall in unison which positively avoids any tilting of the axle and consequent binding of the same in its bearings.

Each of the equalizing pinions is engaged 125 on its upper side by a locking tooth 61 formed on the lower end of a vertically movable locking block 62 which slides in a way 63 on the adjacent part of the main frame. Preparatory to raising or lowering the 130

water wheel the locking blocks 62 are elevated to disengage their teeth from the equalizing pinions in order to release the gear segments, and after such adjustment 5 has been effected the locking blocks are again permitted to descend by gravity into engagement with the equalizing pinions for the purpose of preventing the same from turning and thus supporting the wheel supporting rock arms at their outer ends and thus relieve the adjusting mechanism from undue strain when the apparatus is in operation. The raising of each locking block is effected by an elbow lever 64 pivoted on 10 the adjacent part of the main frame and engaging its elbow with a shoulder 65 on the adjacent locking block, a longitudinally reciprocating gear rack 66 connected by a 15 rod 67 with the elbow lever and guided in a way 68 and a horizontal locking shaft 69 journaled transversely on the main frame and provided with gear pinions 70 which mesh with said gear racks so as to cause the 20 same to slide in unison and operate the locking blocks together. The two guide ways 68 are hung on the shaft 69 and the latter is turned by an upright operating shaft 71 journaled on the main frame and connected at its lower end by a pair of bevel gear 25 wheels 72 with the locking shaft 69, while its upper end is provided with a hand wheel 73.

By employing two water wheels in connection with each of the driving shafts on 30 opposite sides thereof it is possible to transmit power to the same from either one or the other or both of the water wheels according to whether reduced or full power is desired. This power can be further adjusted by raising or lowering either or both 35 of the water wheels relatively to the level of the water. And it is also possible to inspect, adjust and repair one water wheel while the other is in operation so that a 40 complete shut down of the water motor is at no time necessary.

As a whole this motor is comparatively simple considering the work it performs, the same yields a large amount of power for 45 the amount of mechanism employed and the same can also be installed at comparatively low cost.

I claim as my invention:

1. A water power motor comprising a 50 wheel adapted to be immersed in a flowing stream of water, a vertically swinging support on one end of which said wheel is pivotally mounted, a vertically movable slide connected with said support, and means 55 for operating said slide and raising and lowering said support.

2. A water power motor comprising a 60 main frame, a water wheel, a vertically movable support mounted on said frame and carrying said wheel, and means for rais- 65

ing and lowering said support including a vertically movable slide guided on said frame, a line connecting said slide with said support, and an adjusting screw mounted on said frame and engaging with said slide. 70

3. A water power motor comprising a wheel adapted to be immersed in a flowing stream of water, a vertically swinging support on one end of which said wheel is pivotally mounted, a vertically movable 75 slide connected with said support, and means for operating said slide and raising and lowering said support by power derived from said wheel.

4. A water power motor comprising a 80 main frame, a driving shaft journaled in said frame, a vertically swinging support turning about said shaft, a water wheel journaled on said support and operatively connected with said shaft and means for moving said support vertically comprising an intermediate shaft, an intermeshing worm and worm wheel connected respectively with said driving shaft and intermediate shaft and means for transmitting motion 90 from said intermediate shaft to said support.

5. A water power motor comprising a main frame, a driving shaft journaled in said frame, a vertically swinging support turning about said shaft, a water wheel 95 journaled on said support and operatively connected with said shaft and means for moving said support vertically comprising an intermediate shaft, an intermeshing worm and worm wheel connected respectively with said driving shaft and intermediate shaft and means for transmitting motion 100 from said intermediate shaft to said support comprising a guide pulley, a slide guided on said frame, a line connecting said slide and support and passing around said pulley, a screw journaled on said frame and engaging with said slide, a driven gear wheel turning with said screw, and two driving gear wheels splined on said intermediate 105 shaft and adapted to be engaged with and disengaged from diametrically opposite sides of said driven gear wheel.

6. A water power motor comprising a main frame, a driving shaft journaled in said frame, a vertically swinging support turning about said shaft, a water wheel 115 journaled on said support and operatively connected with said shaft, and means for moving said support vertically comprising an intermediate shaft, an intermeshing worm and worm wheel connected respectively with said driving shaft and intermediate shaft, and means for transmitting motion from said intermediate shaft to said support comprising a guide pulley, a slide 120 guided on said frame, a line connecting said slide and support and passing around said pulley, a screw journaled on said frame and engaging with said slide, a driven gear 125 wheel 130

- wheel turning with said screw and two driving gear wheels splined on said intermediate shaft and adapted to be engaged with and disengaged from diametrically opposite sides of said driven gear wheel, and an operating lever connected with said driving gear wheels for shifting the latter.
7. A water power wheel comprising a main frame, a driving shaft journaled in said frame, two supporting arms turning about said shaft, a water wheel having an axle which is journaled at its opposite ends on said arms, means for transmitting motion from said axle to said driving shaft, and means for raising and lowering said supporting arms comprising two vertically movable slides arranged on opposite sides of the motor and guided on the adjacent part of the main frame, lines connecting said slides with the supporting arms on the respective side of the motor, screws engaging with said slides and journaled on the main frame and each provided with a driven gear wheel, two intermediate shafts journaled on the main frame and each operatively connected by a worm and worm wheel with the driving shaft, a pair of driving gear wheels splined on each of said intermediate shafts and adapted to engage and disengage with opposite sides of the adjacent driven gear wheel, two shifting arms each operatively connected with a pair of said driving gear wheels, and a rock shaft journaled on said main frame and carrying said shifting arms.
8. A water power wheel comprising a main frame, a driving shaft journaled in said frame, two supporting arms turning about said shaft, a water wheel having an axle which is journaled at its opposite ends on said arms, means for transmitting motion from said axle to said driving shaft, and means for raising and lowering said supporting arms comprising two vertically movable slides arranged on opposite sides of the motor and guided on the adjacent part of the main frame, lines connecting said slides with the supporting arms on the respective side of the motor, screws engaging with said slides and journaled on the main frame and each provided with a driven gear wheel, two intermediate shafts journaled on the main frame and each operatively connected by a worm and worm wheel with the driving shaft, a pair of driving gear wheels splined on each of said intermediate shafts and adapted to engage and disengage with opposite sides of the adjacent driven gear wheel, two shifting arms each operatively connected with a pair of said driving gear wheels, a rock shaft journaled on said main frame and carrying said shifting arms, and means for locking said lever in position.
9. A water power motor comprising a pair of vertically swinging supporting arms, a water wheel journaled at its opposite ends on said arms, means for causing said arms to move in unison and means for adjusting said swinging arms.
10. A water power motor comprising a pair of vertically swinging supporting arms, a water wheel journaled at its opposite ends on said arms, and means for causing said arms to move in unison comprising segmental gear racks mounted on said arms and each having its row of teeth concentric with the axis of the respective arm, an equalizing shaft provided with gear pinions meshing with said racks, respectively and means for adjusting said swinging arms.
11. A water power motor comprising a pair of vertically swinging supporting arms, a water wheel journaled at its opposite ends on said arms, and means for causing said arms to move in unison comprising segmental gear racks mounted on said arms and each having its row of teeth concentric with the axis of the respective arm, an equalizing shaft provided with gear pinions meshing with said racks, respectively, means for locking said pinions against turning and means for adjusting said swinging arms.
12. A water power motor comprising a pair of vertically swinging supporting arms, a water wheel journaled at its opposite ends on said arms, and means for causing said arms to move in unison comprising segmental gear racks mounted on said arms and each having its row of teeth concentric with the axis of the respective arm, an equalizing shaft provided with gear pinions meshing with said racks, respectively, and means for locking said pinions against turning comprising sliding locking blocks each provided with a tooth adapted to engage with one of said pinions and also having a shoulder, two elbow levers each adapted to engage its elbow with one of said shoulders, means for actuating said elbow levers and means for adjusting said swinging arms.
13. A water power motor comprising a pair of vertically swinging supporting arms, a water wheel journaled at its opposite ends on said arms, and means for causing said arms to move in unison comprising segmental gear racks mounted on said arms and each having its row of teeth concentric with the axis of the respective arm, an equalizing shaft provided with gear pinions meshing with said racks, respectively, and means for locking said pinions against turning comprising sliding locking blocks each provided with a tooth adapted to engage with one of said pinions and also having a shoulder, two elbow levers each adapted to engage its elbow with one of said shoulders, means for actuating said elbow levers and means for adjusting said swinging arms.

cluding two sliding gear racks each connected with one of said elbow levers, and a locking shaft provided with pinions engaging said sliding gear racks and means for 5 adjusting said swinging arms.

14. A water power motor comprising a pair of vertically swinging supporting arms, a water wheel journaled at its opposite ends on said arms, and means for causing said 10 arms to move in unison comprising segmental gear racks mounted on said arms and each having its row of teeth concentric with the axis of the respective arm, an equalizing shaft provided with gear pinions 15 meshing with said racks, respectively, and

means for locking said pinions against turning comprising sliding locking blocks each provided with a tooth adapted to engage with one of said pinions and also having a shoulder, two elbow levers each adapted 20 to engage its elbow with one of said shoulders, means for actuating said elbow levers including two sliding gear racks each connected with one of said elbow levers, a locking shaft provided with pinions engaging 25 said sliding gear racks, and an operating shaft connected by gearing with said locking shaft and means for adjusting said swinging arms.

JOHN V. KRANEBEEL.
